(57) **CLAIM**

The ornamental design for a motorcycle tire tread, as shown and described.

DESCRIPTION

FIG. 1 is a front perspective view of our new motorcycle tire tread design, it being understood that the depicted tread pattern extends over the entire circumference of the tire;

FIG. 2 is front elevation view thereof;

FIG. 3 is a rear elevation view thereof;

FIG. 4 is a right side view thereof;

FIG. 5 is a left side view thereof;

FIG. 6 is a top view thereof; and,

FIG. 7 is a bottom view thereof.

In the drawing figures, the tire features shown in broken lines indicate environmental subject matter only, and form no part of the claimed design.
